UNITED STATES PATENT OFFICE.

CHARLES J. AULBACH, OF PASSAIC, NEW JERSEY, ASSIGNOR TO PASSAIC METAL WARE COMPANY, OF PASSAIC, NEW JERSEY, A CORPORATION OF NEW JERSEY.

CAN-HEADING MACHINE.

Application filed May 17, 1924. Serial No. 714,014.

To all whom it may concern:

Be it known that I, CHARLES J. AULBACH, a citizen of the United States, and resident of Passaic, in the county of Passaic and State of New Jersey, have invented certain new and useful Improvements in Can-Heading Machines, of which the following is a specification.

In some machines for applying ends or heads upon metal bodies, or so-called tin cans, seaming tools are provided for seaming the edges of the bodies and ends together. In some of such machines the seaming tools rotate around the bodies while seaming the ends thereto. In those machines in which the ends or heads are automatically applied upon the can bodies it has been customary, so far as I am aware, to provide stacks of ends or heads and to successively feed the ends from the bottom of the stack to position the ends over or upon the can bodies. A difficulty has been experienced in that the heads do not always freely feed from the bottom of the stack due to the heads sticking together, hence a body may be fed to the seaming devices without having an end or head thereon with resultant crushing of the body and loss of the same, together with the necessity to stop the machine, extract the destroyed body and start the machine again in proper working condition.

The object of my invention is to provide means to feed the ends or heads for the can bodies and apply them thereover successively without having the ends or heads stacked to be fed from the stack, to avoid difficulties above pointed out. Another object is to feed the ends or heads separately and one after another to can bodies disposed in position to receive such ends, and to provide means to stop the feeding of the ends in case a can body should not be fed in position to receive an end, the can bodies preferably being fed successively in timed relation to the feeding of the ends to be applied successively to the said bodies.

My invention comprises novel details of improvement that will be more fully hereinafter set forth and then pointed out in the claims.

Reference is to be had to the accompanying drawings forming a part hereof, where-in-

Fig. 1 is a side elevation of a can seaming

machine embodying my invention, part of 55 the end or head feeding devices being omitted;

Figs. 1^a and 1^b are sectional details illustrating seaming rolls;

Fig. 2 is a plan view;

Fig. 3 is an enlarged detail illustrating means to actuate the can body transerrer or feeder;

Fig. 4 is an enlarged plan view of the end or head feeding means;

Fig. 17 is a partly broken side view of 90 Fig. 16;

Fig. 18 is a cross section of Fig. 17;

Fig. 19 is a partly sectional end view of Fig. 17;

Fig. 20 is a vertical section of the can- 95 body feeding and transferring means;

Fig. 21 is a detail perspective view of the can-body transerrer; and

Fig. 22 is a sectional detail illustrating 100 seaming devices.

Similar numerals of reference indicate corresponding parts in the several views.

I have illustrated my improved means for feeding ends or heads A in conjunction with mechanism for successively feeding can bodies B, including a rotative turret 1, (Figs. 1 and 2), to which said ends and bodies are fed in proper timing for locating the ends on

the turret over the bodies in a successive manner to permit the ends to be seamed upon the bodies. The turret may be rotated step-by-step in consonance with the feeding of 5 the heads and the can bodies by any suitable means well known in the art.

A suitable elongated frame 2 is attached at one end, as at 3, (Fig. 2), to the frame or casting 4 which supports the turret and its 10 operating mechanism. The outer portion of frame 2 is supported and braced by a rod 5 shown pivotally attached at 6, (Fig. 5), to the outer portion of frame 2, said rod being pivotally attached at 7 to a support 8 on frame 4, which may be adjusted by a screw 8^a, (Fig. 1). A feeder for the can-ends A is shown in the form of an endless chain 9 which passes at its forward or delivery end over a sprocket wheel 10 carried by a shaft 11 journaled between the side bars at the inner end of frame 2, said chain at its opposite end passing over a sprocket 12 carried by shaft 13 journaled upon frame 2 at its outer end, (Figs. 4, 10, 16 and 17). The feeder chain 9 is provided with a series of spaced stops or projections 14 shown in hook-like form, (Fig. 10), adapted to engage and push the can-ends A. At the sides of feeder chain 9 frame 2 is provided with spaced guides or ledges 15 for guiding the side edges of the ends A, (Fig. 2), which ends slide upon a longitudinally disposed way 16 that is shown provided with a longitudinal groove 17 through which the upper run of the chain 9 slides and by which it is supported, (Fig. 11). The feeder chain 9 is operated step-by-step to feed can ends A successively to the receivers 1^a of turret 1 upon supporting means or ledges 1^b of the receivers. Loosely 40 mounted on shaft 13 are spaced spur gears 18 in mesh with corresponding racks 19 that extend from a plate or bar 20 that is guided to reciprocate along guide rails 21 secured to frame 2, (Figs. 10 and 11). The gears 18 are provided with projecting arms 22 that 45 pivotally support dogs 23 by means of studs 24, (Figs. 16-19), which dogs are adapted to engage notched disks 25 secured upon shaft 13. When the racks 19 move toward the left 50 in Fig. 17, the dogs 23 will engage the disks 25 to rotate shaft 13 to cause sprocket 12 to advance the feeder chain 9 a step to feed an end A to the turret, and when said racks move in the opposite direction the dogs 23 will be moved reversely to again engage disks 25 for another forward movement of the feeder chain, and so on step-by-step for each end A to be fed. Since can-ends or heads A 55 may vary in length I prefer to provide the feeder disks each in two members 25^a and 25^b secured together by rivets 25', (Fig. 18), the disks of each pair having notches 25^c, 25^d respectively unequally spaced, (Fig. 17), say 60 three of such notches on disk 25^a and two of such notches on disk 25^b. When the dogs 23

are placed as shown in Fig. 16 they will engage the outer disks 25^a to actuate the feeder chain for one extent of feed for each step, and when it is desired to cause the feeder chain to operate for a different length feed 70 the position of the dogs is reversed on the respective arms 22, so that the dogs will engage the disks 25^b. A detachable protecting cover is shown at 26 enclosing the gearing, dogs and racks described over a shield 27 75 carried at the outer end of frame 2.

While I have shown two racks 19 and corresponding dogs 23 and disks 25, it will be understood that they are used in duplicate to balance the operation of the feeder chain, 80 but if desired one set of corresponding devices may be used for the purpose.

Means for operating the feeder chain 9 are arranged as follows:—From the forward end of plate 20 a pin 28 depends, 85 (Figs. 10, 11 and 13). The pin 28 is shown provided with a head 28^a secured to plate 20 by screws 29, (Fig. 11), said head having an opening through it at 28^b through which the lower run of feeder chain 9 passes and rests upon a guide bar 30 that is located within opening 28^b. Said guide bar is carried by a sub-frame 31 secured within frame 2 below the feeder chain, (Figs. 10, 11, 13 and 14). The frame 31 is shown supported 90 upon frame 2 by screws 32, (Fig. 11). The pin 28 is moved in one direction, (to the right in Fig. 10), by means of a slidable member 33 adapted to push said pin, which member is guided to slide upon spaced guide rails 34 that are shown supported by the bar 30 by means of bolts 35 passing through the bar 30 and rails 34, (Figs. 10 and 14). The pin 28 is adapted to travel back and forth between the guide rails 34, (Fig. 11). The slidable member 33 is provided with a depending projection or pin 36 shown secured to member 33 by a screw 37, said projection having shoulders at 38 bearing against the lower edges of rails 34. (Fig. 15). A link 39 is pivotally attached to the projection 36 by means of pin 40 which also retains a sleeve 41 on said projection. Link 39 is pivotally connected with a crank arm 42 carried by shaft 43 journaled upon bracket 44 supported by frame 2. A crank arm 45 on shaft 43 is pivotally connected with a pitman 46 that is pivotally connected with a crank pin 47 carried by a sprocket wheel 48 driven by a chain 49 that may be driven by a sprocket wheel operated by any desired power transmitting part of the machine, such as by shaft 69^a, (Fig. 20), whereby when the pitman 46 is operated the member 33 will be reciprocated, (Fig. 1). A feeding-hook 50 is adapted to engage pin 28, (Fig. 14), and is pivotally carried by projection 36, the lateral arm 50^a of the feeding hook being shown resting upon sleeve 41, beneath enlargement 38^a of projec- 110

115

120

125

130

tion 38, whereby the hook is supported to rock, (Fig. 15). The hook 50 has a forward beveled edge 50^b adapted to engage a rockable finger 51 designed to move the hook laterally to prevent it from engaging the pin 28 when a cam body B is not fed to receive an end or head A, whereby to prevent feeding movement of feeder chain 9. The finger 51 is normally out of the path of the hook 50, or depressed, as indicated in Figs. 10 and 13, and the feeding hook is normally retained in position to engage pin 28, in the position shown in Figs. 6 and 14, by means of spring 52 shown attached to pin 53 on slide member 33 and to pin 54 on the hook, (Figs. 13 and 14). When can bodies are being fed successively to the turret the finger 51 will be retained depressed out of the path of hook 50, (Fig. 13). When a can body does not pass in its proper order of succession to the turret the finger 51 will rise into the path of hook 50 so that the beveled edge 50^b of the hook will approach and engage finger 51, (Figs. 6 and 7), near the limit of the corresponding stroke of slide member 33, whereby the hook 50 will be moved to one side from operative position with relation to pin 28, (Fig. 8), to be retained from engagement with said pin on the next forward stroke of member 33 to the left in Fig. 8, so as not to pull pin 28 and thereby not operate feeder chain 9, since finger 51 extends along one side of pin 28 so that the tip end of the hook will slide past said pin on the stroke to the left in Fig. 8, leaving the racks 19 and chain 9 unoperated during the absence of a can body in the appropriate position. The finger 51 is secured upon a rock shaft 55 journaled upon bracket 44, (Figs. 1, 5 and 13). Shaft 55 is provided with a crank arm 56 connected by link 57 with crank arm 58 secured upon a vertical shaft 59 journaled upon bracket arm 44^a and shaft 59 has a crank arm 60 connected by link 61 with bell crank lever 62 that is pivotally supported at 63 upon frame 64 of the can body feeding mechanism, (Figs. 1 and 2).

The frame 64 extends outwardly from the frame or casting 4 at an angle to frame 2 and is provided at its outer end with a standard 65 so that the can bodies may be fed to the can feeding mechanism. The can-body feeding means illustrated comprises an endless belt or conveyor 66 shown mounted upon roller 67, 68, 69, (Fig. 1), journaled upon the frame. An idle pulley 70 carried upon a lever 71 journaled upon the main frame and operated by spring 72 serves to maintain desired tension in conveyor belt 66, (Figs. 1 and 20). At the sides of belt 66 are located spaced walls 73 extending above the belt, supported by frame 64, whereby the containers or can bodies B are guided. Said conveyor belt may be driven continuously in any desired way. A driving shaft 74 has a gear 75 in mesh with gear 76 secured on shaft 77 journaled in suitable bearings on the main frame, which shaft is provided with gear 78 in mesh with gear 79 on shaft 76 of roller 67, whereby the conveyor belt may be driven continuously. The open end can bodies B may be delivered to the conveyor to lie horizontally thereon by any suitable means, or manually. The conveyor is adapted to feed the can bodies to a transferrer 80 rotatively carried by shaft 81 journaled in suitable bearings on the frame. The transferrer is adapted to rotate to successively raise the can bodies delivered thereto from a horizontal to an upright position, so that the open ends will be elevated into a position to receive the ends or heads A to be seamed to the body. The transferrer may be of any desired construction and is shown comprising spaced fingers 80^a having curved projections 80^b adapted to operate in spaced slots 82 in a plate 83 secured upon the main frame in substantial alignment with the upper run of conveyor 66 to receive the can bodies therefrom, (Figs. 20 and 21). The transferrer is shown provided with stops 80^c to obstruct the can bodies as they are advanced to the transferrer by the conveyor, (Fig. 20). In the body receiving position the transferrer is located as indicated in Fig. 20, with its arms 80^c substantially within the slots 82 of plate 83 and the fingers 80^b below. When the transferrer is rotated to turn the can body to a vertical position, with its open end uppermost, the fingers 80^b will obstruct the advance of can bodies to the conveyor until said fingers are again lowered, (see the dotted position of the transferrer in Fig. 20).

In the example illustrated the transferrer 80 is rotated back and forth for the purpose of alternately receiving the can bodies and turning them upwardly. For such purpose I have shown shaft 81 provided with a gear 84 in mesh with a rack 85 that is pivotally connected at 86 with a reciprocative rod 87 that is operated by a cam 88 secured on shaft 67^a, (Figs. 2 and 3). By preference, rod 87 is provided with resilient means to actuate the rack 85, for which purpose said rod is shown made in two parts 87^a and 87^b, (Fig. 3), having relative movement and provided with an interposed spring 89, shown coiled around rod part 87^a and slidably in a bushing 90 carried by a cylinder 91 containing said spring, the rod part 87^a having a piston-like head or stop 92 between which head or stop and the bushing 90 the spring 89 is located. The rod part 87^b is shown secured by a nut or head 93 to cylinder 91. Air in cylinder 91 between heads 92 and 93 aids rod part 87^b in pushing rod part 87^a to actuate the rack in one direction, the spring 89 actuating the rack in the other direction. A

port 94 in cylinder 91 permits flow of air into and from the cylinder. A spring 95, shown coiled around rod part 87^a, bears against bushing 90 and against bearing 96 for moving rod part 87^a, (Fig. 3). The rod part 87^b is shown provided with a slotted head 97 slidable on shaft 67^a and provided with a projection 98 operative in the cam groove 88^a of cam 88, (Fig. 3). When said cam is rotated the rack 85 will be reciprocated to rotate transferrer 80 back and forth, the springs 89 and 95 resiliently resisting operation of the rack by cam 88 so that the transferrer will not injure the can bodies. 10 When the transferrer is rotated to raise a can body to a vertical position the latter is brought to rest at its side against a wall or stop 99, (Fig. 20). Said wall or stop may be adjusted with respect to the trans- 15 ferrer by means of slots 99^a in the base of the wall and screws 100 shown passing through said slots and secured to the main frame, (Figs. 2 and 21).

When a can body is presented on end with 20 its open end upwardly disposed it will be in position to be transferred to a receiver 1^a of the turret 1. The turret is carried by a shaft 101 journaled in the main frame 4, which turret may be rotated step-by-step by 25 any well known mechanism utilized in can seaming machines, (Fig. 2). The receivers or pockets 1^a of the turret are shown radially disposed below the ledges 1^b and have their outer sides open to receive the can bodies 30 which rest on the plate 83, beneath can ends supported by the ledges 1^b, (Fig. 20). Means are provided to push the can bodies from the transferrer into the turret. In the example 35 illustrated a pusher or plunger 102, (Fig. 2), is located in register with a pocket 1^a of the turret and is shown comprising a suitable head upon a reciprocating rod 103 guided by bearing 104 supported by the frame, the rod being adapted to be reciprocated to 40 push the can bodies from the transferrer to the pockets of the turret. Any suitable means may be provided for reciprocating the pusher or plunger 102. A forked arm 105 pivotally supported on shaft 106 journaled in bearings in the main frame receives 45 lateral projections 107 extending from rod 103, (Fig. 1). The shaft 106 is shown provided with a crank-arm 108 pivotally connected with block 109 slidable on a rod 110. 50 The rod 110 has a stop 111 against which a spring 112 bears, said spring also bearing against block 109, the latter being retained on the rod by a nut, whereby said rod may resiliently push the block to operate the 55 pusher or plunger 103. The rod 110 is pivotally connected with a crank-arm 113, (Figs. 2 and 20), pivotally supported at 60 114 on the main frame, which crank-arm is provided with a projection 115 cooperative 65 with a cam 116 on shaft 77. Said cam is

timed to cause operation of pusher or plunger 103 through the connecting parts described, so that when a can body has been presented by transferrer 80 in position to register with pocket 1^a of turret 1, said pusher will push the can body into the receiver and will recede from the transferrer, which will operate to receive another can body and present it in register with a receiver of the turret just after the pusher has been retracted from relation to the transferrer, and so on. 70 75

When the machine is in operation the can bodies B are fed successively to the trans- 80 ferrer by the conveyor or belt 66, and the ends or heads A are fed correspondingly and successively to the ledges 1^b of the turret, in timed relation one to another, the turret being rotated step-by-step for each can body and head to be seamed. The arrangement 85 is such that each time that the turret comes to rest an end or head A will be presented into a receiver of the turret, the receivers being provided with open supporting ledges at 1^b at the upper parts of the receivers beneath the ends A, for the ends A, so that the flanges A' of the ends A may rest on the ledges to expose said ends to the bodies B that are pushed by plunger 102 from the transferrer 80 into position in the receivers, 90 which bodies rest on the table C beneath the turret receivers so as to be slid around by the turret. At 117 is a guide curved around along the exterior of and spaced from the turret in position to engage the outer end 95 of the ends A when the latter are deposited upon the ledges 1^b of the turret receivers, (Fig. 2), from which the ends A project when fed by the feeder chain 9. The guide 117 is eccentrically disposed or cam-like with respect to the axis of the turret, with the end of the guide that is near the feeder chain 9 farther from the turret than its opposite end, so that as the turret rotates the ends A carried thereby, (that are not pushed inwardly 100 in the receivers to the limit by chain 9) will, by the guide 117, be slid along the ledges 1^b to the proper inward position therein as the turret rotates. Guides 118 are located outside of the turret beyond the guide 117 to 105 keep the ends or heads A in position in the turret until they are brought to rest with the can bodies therebeneath at the point D, (Fig. 2), where the bodies and ends are 110 seamed together. Each time that a can body is deposited in the transferrer 80 the latter will rock to tilt the body from a horizontal position to a vertical position with an open end extending upwardly, (Fig. 20), where- 115 upon plunger 102 will operate to push the body into a receiver of the stationary turret beneath an end A that has been delivered to the corresponding end supporting means or ledge 1^b of the turret. The trans- 120 ferrer 80 will then be moved into position to receive 125 130

another body B and after the turret rotates a step another end A will be brought to rest in position to be above such body B that is to be pushed by plunger 102 into the corresponding receiver of the turret, and so on successively.

The turret operates step-by-step regardless of whether a can body has been presented in a receiver or not, and it is an object of my invention that an end A should not be fed into a receiver of the turret in the event that an appropriate can body should not pass in the proper position for such end A, for which purpose the feeder 10 chain 9 will be stopped from its feeding movement so as not to feed an end A in the absence of a body to correspond with such end A. To cause the feeder chain 9 to stop at the proper time the arm 62^a of the bell 15 crank lever 62, (Fig. 2), is located in position to pass through an opening at 119 in the corresponding wall 73. Said arm will be operated by the bodies B when passing the arm, said arm 62^a being shown provided with 20 a roller 62^b to engage the can bodies. When the can bodies engage the roller 62^b the bell crank 62 will be operated to cause the finger 51 to be depressed out of the path of hook 50, so that said hook during its movement 25 to the left in Fig. 10, may pull pin 28 to operate the feeder chain 9 a step, and on the return stroke the slide 33 will operate said pin to push the racks 19 reversely ready for the next feeding step, and so on. If a can 30 body does not pass roller 62^b the arm 62^a will be moved by spring 120 to cause said arm to pass through wall 73, whereupon the finger 51 will be raised to the position shown in Fig. 7, so that when hook 50 engages said 35 finger on the return stroke said hook will be disengaged from pin 28, (Fig. 8), and will not engage said pin on the next forward stroke of the hook, so that the racks 19 will not be moved and the feeder chain 40 will remain at rest. When a can body next operates arm 62^a the latter will cause the finger 51 to descend from the path of the hook 50 so that the latter on its next stroke toward pin 28 may engage the same and 45 snap behind it, to the position shown in Figs. 6 and 14, ready to operate the feeder chain 9 to feed an end A to a receiver of the turret corresponding to the last named can body. The pin 63 that pivotally supports 50 crank arm 62 is shown carried upon an adjustable arm 63^a having slot 63^b receiving screws 63^c carried by frame 64, whereby the position of the bell crank 62 may be adjusted according to the character of the bodies A 55 to be fed, (Fig. 2). By not feeding an end A to the turret in the absence of a corresponding can body danger that seaming tools would engage such an end A without a corresponding body is avoided, hence difficulties heretofore experienced in feeding can

ends or heads in the absence of a body, or feeding bodies in the absence of an end or head, are avoided.

Any appropriate or well known seaming tools may be provided for seaming the flange 70 of the bodies and their ends A together. Spaced seaming rolls 121 are supported over a suitable part of the turret, indicated in dotted lines in Fig. 2, and driven by intermeshing gears 122 carried by shafts 123, 75 124, (Fig. 22), which parts may be supported and rotated in any desired manner to cause the seaming rolls to act upon the edges of the end A and the can body to seam them together in a well known way, 80 such as indicated in Figs. 1^a, 1^b.

Any suitable means may be provided for elevating the can bodies with their closures or ends A thereon to the seaming tools, such as by means of a reciprocatory lifter indicated at 125 adapted to be operated by a reciprocatory rod 126, (see dotted lines in Fig. 20), to be actuated in any suitable or well known way to raise and lower the can bodies when the turret comes to rest. The 90 seaming devices and lifter which form part of the seaming mechanism, will be caused to operate in timed relation to the step-by-step movements of the turret to cause seaming the ends A to the can bodies at each stop 95 of the turret.

After the closures or ends A have been seamed to the can bodies the latter may be ejected from the turret by any suitable or well known means or manually, and may be received on a conveyor to carry them away, or may be delivered in any other suitable manner. At the delivery point a wall 127 obstructs the seamed can bodies, (Fig. 2), where a suitable conveyor 128, 100 such as a belt, may receive the can bodies to deliver them where desired, or to another seaming machine where such machines are arranged in tandem to first seam an end A to one end of a can body and thereafter to 105 seam another end at the opposite open end of the can body. The conveyor or belt 128 may be supported similarly to conveyor 66, one end of the conveyor 128 being shown passing over a roller 129 whose shaft 130 110 is supported by bracket 131 is provided with a sprocket wheel 132 receiving chain 133 from drive sprocket 134 on shaft 69^a of roller 69 operated in consonance by and with the conveyor 66, (Fig. 20). When the can 115 bodies are delivered upon the conveyor belt 128 they may be turned on their sides so that the then open ends extend rearwardly and may be fed by said conveyor successively to a second transerrer associated with 120 a second turret, which seaming devices have end feeding mechanism of the character described, which transerrer will operate to turn such can bodies upwardly with the open ends uppermost, and the previously 125

closed ends downwardly disposed, in position to be pushed by a corresponding pusher 102 into the associate turret, which mechanism similar to the end feeder mechanism 5 set forth may feed ends in the manner stated to be seamed to the can bodies in manner before described. Such arrangement enables the continuous operation of containers or can bodies to have the closures or ends 10 applied and seamed at opposite ends without any manual handling from the time the bodies and ends are placed upon the respective conveyors.

One of the advantages of my invention 15 is that the feeding of the ends A may be accurately determined because the operator may place the ends A manually upon the feeder chain 9 in position to be fed by the appropriate stops or pushers 14, and as such 20 feeder chain is in plain view of the operator assurance may be had that the ends A will be on the feeder chain in proper successive order, and there will be no danger that two superimposed ends A will be simultaneously fed to the turret, and no jamming or 25 crowding of the ends will take place since the ends A are not fed from a stack of ends and clogging of the machinery or injury thereto from improperly fed ends A 30 is avoided.

In order to apply lubricant to the ends as 35 they are fed by the feeder chain 9 I provide a roller 135 shown having a peripheral groove adapted to correspond to the shape 40 of the ends A, which roller is pivotally supported upon brackets 136 secured upon frame 2, so that the roller may make contact with the surface of the ends. A distributing roller 137 in contact with roller 45 135 is pivotally carried by brackets 136. The shafts of said rollers are shown supported in slots in said brackets so that the rollers may be readily removed and replaced according to the shape of the ends A being 50 fed. The rollers 135 and 137 may be supplied with a suitable lubricant, such as soapy water, by any suitable means, such as from a sight gage 138 suitably supported over the rollers, as indicated in dotted lines 55 in Fig. 5. The frame 2 is shown provided with downwardly and outwardly disposed passages 2', (Fig. 12), through which the excess lubricant may flow.

The can body feeding devices and the 55 general construction of the turret and the seaming devices form no specific part of my present invention beyond their combination with my improvements, as such parts are substantially the same as set forth in the 60 application of Charles Gueritey, filed November 27, 1922, Serial No. 603,610, for means for feeding can bodies.

Having now described my invention what 65 I claim is:—

1. The combination of seaming mecha-

nism, a rotative turret provided with receivers for can bodies and having means to support can ends over the bodies, and means to feed said bodies to said receivers, with means for feeding can ends to said supporting means, comprising means to guide ends successively, a feeder provided with means to push said ends, and means to operate said feeder step-by-step in consonance with the 70 operation of the seaming mechanism. 75

2. The combination of seaming mechanism, a rotative turret provided with receivers for can bodies and having means to support can ends over the bodies, and means to feed said bodies to said receivers, with 80 means for feeding can ends to said supporting means comprising means to guide ends successively, a feeder provided with means to push said ends, means to operate said feeder step-by-step in consonance with the 85 seaming and body feeding mechanism, and means operative in the absence of a can body in said body feeding mechanism to stop the operation of the end feeder. 90

3. The combination of seaming mechanism, a rotative turret provided with receivers for can bodies and ends, and having means to support can ends over the bodies, and means to feed said bodies to said receivers with an endless feeder for can ends 95 provided with means to push said ends, means to guide said ends to the supporting means, means to operate said endless feeder in consonance with the seaming and body feeding mechanisms, and means operative in the absence of a can body in said body feeding mechanism to stop the operation of the endless feeder. 100

4. The combination of seaming mechanism including a rotative turret provided with receivers for can bodies and ends, with an endless feeder for said ends provided with means to push the ends to said receivers, wheels supporting said feeder, a reciprocative bar provided with a rack, a gear cooperative with said rack, a dog connected with said gear, a toothed disk cooperative with said dog and connected with one of said wheels, means to reciprocate said bar, a pin extending from the bar, a reciprocative member provided with a hook, said member and hook being cooperative with said pin to reciprocate the bar, and means to cause the hook to release the pin in the absence of a can body corresponding to 110 a can end. 115

5. The combination of seaming mechanism including a rotative turret provided with receivers for can bodies and ends, with an endless feeder for said ends provided with means to push the ends to said receivers, wheels supporting said feeder, a reciprocative bar provided with a rack, a gear cooperative with said rack, a dog connected with said gear, a toothed disk co- 120 125 130

- operative with said dog and connected with one of said wheels, means to reciprocate said bar, a pin extending from the bar, a reciprocative member provided with a hook, 5 said member and hook being cooperative with said pin to reciprocate the bar, a finger adapted to cooperate with said hook to release it from said pin, and means normally tending to retain the finger in operative relation to the hook, to cause the hook to release the pin in the absence of a can body corresponding to a can end, said means being operative by a can body to move the finger out of operative relation to the hook.
- 15 6. The combination of seaming mechanism including a rotative turret provided with receivers for can bodies and ends, and means to supply can bodies successively to the seaming mechanism, with an endless 20 feeder for said ends provided with means to push the ends to said receivers, wheels supporting said feeder, a reciprocative bar provided with a rack, a gear cooperative with said rack, a dog connected with said gear, a toothed disk cooperative with said dog and connected with one of said wheels, means to reciprocate said bar, a pin extending from 25 the bar, a reciprocative member provided
- with a hook, said member and hook being cooperative with said pin to reciprocate the 30 bar, a finger adapted to cooperate with said hook to release it from said pin, and means having a portion normally in the path of bodies in said supply means for retaining the finger in operative relation to the hook to release it from the pin in the absence of can bodies, said portion of the last named means being operative to cause said finger to move out of operative relation to the hook when engaged by a can 35 body.
7. The combination of seaming mechanism including a rotative turret provided with receivers for can bodies and ends, with an endless feeder for said ends arranged 40 to deliver the ends to said receivers, means to operate said feeder step-by-step in consonance with the operation of the turret, and a curved guide adjacent to the turret, said guide having a portion adjacent to the 45 delivery end of said feeder, another portion of said guide being nearer to the turret than its first named portion to push ends into receivers of the turret during rotation of the latter.

CHARLES J. AULBACH.
